Des. 195,541
Patented July 2, 1963

195,541

LADY'S SLIP OR THE LIKE

Neva A. Cederholm, Chicago, Ill., assignor to Kellwood Company, Chicago, Ill., a corporation of Delaware

Filed Sept. 24, 1962, Ser. No. 71,824

Term of patent 7 years

(Cl. D3—26)

Fig. 1.

Fig. 2.

FIG. 1 is a front elevational view of a lady's slip, showing my new design; and

FIG. 2 is rear elevational view thereof.

The dominant features of my design reside in the portions shown in full lines.

I claim:

The ornamental design for a lady's slip or the like, as shown and described.
